COUNTING MECHANISM

John Handley, Purley, England, assignor to The Union Totalisator Company, Limited, Glasgow, Scotland, a corporation of Great Britain

Application October 11, 1952, Serial No. 314,291
In Great Britain July 12, 1951

2 Claims. (Cl. 235—134)

1

This invention relates to improvements in counters or aggregators for totalisators, and is more particularly concerned with mechanism for transferring stepwise impulses from a digital denominational shaft of lower order to one of higher order.

In the construction described in the specification of the prior United States Patent No. 2,100,164 dated November 23, 1937, a digit transfer device includes a snail cam carried by a lower denominational shaft and engaged by a cam follower which rocks a spring-urged lever carrying a pin engageable with a toothed wheel feeding a higher denominational shaft. This pin is controlled by a control plate which, operated by way of mechanical linkage from the snail cam, presses the pin into an interdental space of the toothed wheel when the cam causes it to be moved for transfer purposes. After transfer has been effected the linkage returns the control plate to its initial position. This arrangement suffers from the disadvantage that the locking and unlocking movement of the control plate is not sufficiently rapid to free the transfer pin before the snail cam in its continued travel attempts to move it to the position for the next transfer.

It is an object of the construction of the present invention to overcome this disadvantage.

The figure of the accompanying drawing is a perspective view of a mechanism according to the invention.

Referring to the drawing, 1 denotes a shaft portion of a lower denominational spindle which revolves in the direction of the arrow, e. g., a unit spindle, 2 is a shaft carrying a ten-toothed sprocket wheel 3 which is a feed wheel for the higher denominational spindle, in the example quoted the tens spindle. Mounted on the shaft 1 are three cams 4, 5 and 6, respectively. Of these, the cam 4 is a snail cam which actuates a transfer pawl pin 7 by way of a cam follower 8 and a spring-urged lever 9. The lever 9 is pivoted at 10 to a part 11 of a frame to which is anchored a spring 12 acting on the lever 9.

Cam followers 13 and 14 tracking cams 5 and 6, respectively, are mounted on arms 15 and 16, respectively, of a Y-shaped member pivoted at 17 to the frame. Connected to an extension 25 of the arm 15, 16 is one end of a link 18 of which the other end portion is widened to form a control plate 19. The plate 19 carries two detent-forming pins 20 and 21 which, in the periods between transfers, lock the wheel 3 against rotation. In these periods the plate 19 is in its position furthest from the shaft 1. The plate 19 is shown in the transfer position, that is, in the

position nearest to the shaft 1. The plate 19 has two slots 22 and 23, one 22 of which surrounds but does not contact the shaft 2. The transfer pawl pin 7 fixed to a link 24 pivoted to the lever 9, runs in the slot 23 in the control plate 19.

The shaft 1 is shown at the position occupied when the digit displays zero, the follower 8 resting in the root of the cam 4. At this position the lever 9 has lifted the link 24 to its highest position and the pawl pin 7 is engaging the sprocket wheel 3.

As the shaft 1 commences to rotate, the cam 6 engaging the follower 14 rocks the member 15, 16 on the pivot 17, so that the arm 25 moves the link 18 to the right. As the pawl pin 7 is controlled in the slot 23, it is carried clear of the teeth of the sprocket wheel 3, and at the same time the pins 20, 21 straddle a tooth of the wheel 3 and thus prevent the wheel 3 from moving when the pawl pin 7 is disengaged.

The cam 5 is so shaped that the follower 13 moves towards the shaft 1 as the follower 14 is moved away by the cam 6.

As the shaft 1 continues to turn, the follower 8 is steadily lifted by the cam 4, until the lever 9 has lowered the link 24 to bring the pawl pin 7 to the bottom of the slot 23.

At this point the cam 5 moves the follower 13 away from the shaft 1, and the cam 6 allows the follower 14 to move towards the shaft 1, so that the arm 25 moves the link 18 to the left, re-engaging the pawl pin 7 with the wheel 3, and disengaging the pins 20, 21, and then, as the shaft 1 completes its revolution, the follower 8 drops to the root of the cam 4, urged by the spring 12, and the sprocket wheel 3 is moved through one tenth of a revolution by the pawl pin 7.

Thus, the control plate 19 forming part of the reciprocatory guide link is given a quick "engage" or transfer movement when the pin 7 comes into operative engagement with the sprocket wheel 3, then a dwell during which the pin 7 pulls the wheel 3 through one tooth distance, then a quick "disengage" or locking movement when the stop pins 20, 21 engage the sprocket wheel 3, then a dwell pending the next transfer, then a quick "engage," and so on.

What is claimed is:

1. A mechanism for transferring stepwise impulses from a digital denominational shaft of lower order to one of higher order, comprising first cam means connected to rotate with said shaft of lower order, a toothed wheel capable of rotating said shaft of higher order, a spring-urged lever actuated by said first cam means, a

pin engageable with said toothed wheel and linked to said lever, a reciprocatory guide link controlling said pin, second cam means rotated by said shaft of lower order, a Y-shaped cam-follower embracing and co-operating with said second cam means and connected to said guide link for reciprocating said guide link rapidly in opposite directions when said spring-urged lever is at predetermined positions near the beginning and the end of its operative travel, the conjoint effect of the spring-urged lever and the reciprocatory guide link being to impart a stepwise

10

rotation to said toothed wheel to rotate the shaft of higher order when the shaft of lower order has been partially rotated through a predetermined angle.

5. 2. A mechanism as claimed in claim 1, wherein in the link incorporates a control plate formed with a guide slot engaged by the pin, and formed with a further slot which surrounds the shaft of lower order.
